UNITED STATES PATENT OFFICE

GUSTAV BORGESON, OF SYRACUSE, NEW YORK, ASSIGNOR OF ONE-HALF TO ANELLA L. RIDGELY, OF SYRACUSE, NEW YORK

HEATER GRATE

Application filed November 1, 1928. Serial No. 316,422.

This invention relates to a fuel grate for hot air, hot water or steam heaters and is adapted to be installed in the combustion chambers of old or new heaters without material alteration thereof other than the possible replacement of the conventional type of grate most commonly employed.

The main object of my improved grate is to permit the efficient and economical use of various grades of coal and particularly the finer and less expensive grades of either bituminous or anthracite coal as well as the inferior grades of both classes in such manner that the inflammable products of the fuel may be distilled out of the residue and entirely consumed thereby assuring a maximum consumption of the inflammable products and incidentally reducing to a minimum the smoke content escaping through the chimney or stack, the net result being a far greater economy in the use of the fuel and elimination of the smoke nuisance.

One of the specific objects is to use relatively narrow upright grate bars in the formation of the side walls of the fuel basket so that the size of the basket may be readily increased or diminished as may be required for combustion chambers of different sizes by simply increasing or decreasing the number of upright grate bars and permitting them to be assembled edge to edge to conform to different forms of combustion chambers such as circular, elliptical or rectangular.

Another object is to provide the meeting edges of the upright grate bars with interlocking connections arranged so that they may be interlocked with each other by relative vertical sliding movement of adjacent bars or sections.

40 A further object is to standardize the form and size of the bar-sections so that each may be cast in one and the same mold.

Another object is to provide means for supporting a relatively small number of the upright grate bars upon an underlying support and to provide the meeting edges of all of the bars with means whereby the remaining bars will be supported by each other independently of the underlying support.

50 Another object is to provide the basket

with separate bottom sections relatively rotatable in a horizontal plane about a vertical axis and to provide said sections with radial perforated segments or sectors in uniformly spaced relation circumferentially and of approximately uniform area so that the sectors may be moved rotarily into and out of registration with the segments of the other section and also into and out of registration with the spaces between the segments of said other section to permit shaking of the rotary grate section without dumping and also to permit dumping of the fuel or residue from the grate sections when desired.

Another object is to provide a more convenient means for assembling and supporting the entire grate than has heretofore been practised in the use of grates of this type.

Other objects and uses relating to specific parts of the grate as a unitary article of manufacture will be brought out in the following description.

In the drawings:—

Figure 1 is a top plan view of a fuel grate embodying the various features of my invention but omitting the operating means for shaking and dumping the rotatable grate section.

Figure 2 is a sectional view taken in the plane of line 2—2, Figure 1.

Figures 3, 4, 5 and 6 are horizontal sectional views taken respectively in the planes of lines 3—3, 4—4, 5—5 and 6—6, Figure 2.

Figures 7, 8 and 9 are enlarged detail horizontal sectional views taken respectively in the planes of lines 7—7, 8—8 and 9—9, Figure 2.

Figure 10 is an enlarged detail vertical sectional view taken in the plane of line 10—10, Figure 2.

Figure 11 is an enlarged detail vertical sectional view taken in the plane of line 11—11, Figure 5.

Figure 12 is a detail sectional view taken in the plane of line 12—12, Figure 11.

Figure 13 is a detail sectional view taken in the plane of line 13—13, Figure 12.

Figure 14 is a detail sectional view of adjacent upright basket sections showing the manner of supporting said sections one upon

the other, portions of the sections being shown in section.

As illustrated, this grate unit comprises a pair of tubular supporting bars —1— arranged in a horizontal plane and in parallel spaced relation at opposite sides of and equal distances from the vertical axis of the grate and adapted to be supported at the ends in suitable bearings, not shown, on the interior 10 of an ash box or equivalent part of the heater below the combustion chamber, said bars being preferably of uniform length and arranged to extend forwardly and rearwardly relatively to the front side of the heater.

15 Each bar —1— carries a pair of collars —2— slidably adjustable thereon to properly position them for receiving and supporting a superstructure presently described but when properly adjusted will be disposed in 20 vertical planes at the front and rear of the vertical axis of the grate and uniform distances from said axis, as shown more clearly in Figure 5.

The collars of each pair are provided with 25 upwardly projecting bosses —2'— extending across the adjacent portions of the bar at angles of approximately forty-five degrees thereto and in planes which converge toward the axis of the grate at an angle of approximately ninety degrees to each other, said bosses being provided with grooves —2''— in their upper sides at the same angle to the corresponding bar and to each other.

These collars —2— and their channeled 35 bosses —2'— constitute what may be termed saddles for receiving and supporting a corresponding number of arms —3— which are seated in the grooves —2''— to extend inwardly therefrom radial to the axis of the 40 grate and are integrally united at their inner ends to a tubular hub —4— which is coaxial with said axis and together with the arms —3— constitute what may be termed a spider for supporting an additional superstructure, 45 as shown in Figure 5.

The arms —3— are preferably T-shaped in cross section and extend from the base of the grooves —2''— some distance above the upper faces of the bosses —2'— for receiving 50 and supporting a superposed relatively stationary lower grate section —6— having a central hollow hub —7— and a plurality of, in this instance four, radially projecting plates or sectors —8— which are arranged in 55 the same horizontal plane above and parallel with the arms —3— and are spaced uniform distances apart circumferentially, as shown more clearly in Figure 4.

The opposite longitudinal edges of each 60 plate or sector —8— diverge outwardly from the hub and their outer ends are, therefore, wider than their inner ends, the surface area of each plate or sector being relatively greater than the area of the intervening space as 65 —8'—.

The outer marginal edges of the plates or sectors —8— are mainly concentric with the axis of the hub —7— and equal distances therefrom and extend through arcs of slightly more than forty-five degrees while the angle of the spaces —8'— between the sectors is slightly less than forty-five degrees, the objects of which is to permit similar sectors of an overlying upper grate section —9— to cover said spaces when adjusted to one position and to substantially register with the sectors —8— when adjusted to another position as will be hereinafter more fully described, see Figure 3.

The hub —7— of the lower grate section —6— is seated over and upon the upwardly projecting hub —4— and is adapted to rest upon the upper surfaces of the arms —3—, as shown in Figure 2, with the upper surface of the sectors —8— in nearly the same horizontal plane as the upper end of the hub —4—.

The intermediate portions of the sectors —8— are provided with downwardly projecting flanges —10— equal distances from the axis of the hub —7— and adapted to rest upon the upper surface of the arms —3—, the lower ends of said flanges being grooved to receive the T-shaped head of the arms —3— so that the opposite edges of each flange may be provided with extensions —10'— engaging opposite sides of the upper portions of the arms —3— for holding the lower grate section —6— against rotary movement while permitting it to be readily placed from the top downwardly in operative position on the spider or removed vertically therefrom.

The outer ends of the plates or sectors —8— are provided with central circumferentially elongated slots —11—, Figures 3 and 4, for receiving the lower ends of certain grate bars of the fuel basket hereinafter described and holding those bars in operative position, see Figure 2.

The upper grate section —9— comprises a hollow hub —12— and a series of radially projecting plates or sectors —13— somewhat similar to the plates or sectors —8— of the lower grate section —6— in that they are arranged in uniformly spaced relation circumferentially in a plane just above the upper surface of the lower grate section —6—, Figure 2, so as to overhang the upper end of the hub —4—.

The upper end of the hub —4— is provided with a ball race for receiving a circular series of anti-friction balls —14— upon which the overlying portion of the upper grate section —9— is adapted to rest for relative rotary movement with a minimum friction, the central portion of the upper grate section —9— being provided with an annular flange —9'— surrounding the circular series of balls —14— to reduce the liability of accumulations of ashes in or upon the ball bearings, Figure 2.

The plates or sectors —13— are somewhat shorter radially than the underlying plates or segments —8— but have their opposite edges divergent outwardly from the hub —12— and their outer marginal edges concentric with the axis of the hub as shown in Figures 1 and 3.

The outer ends of the plates or sectors —13— are, therefore, of greater circumferential width than the intervening spaces and each extends through an arc slightly greater than forty-five degrees while the angle of the space between the sectors is slightly less than forty-five degrees.

The upper grate section —9— is capable of oscillation about a vertical axis for shaking the ashes from the superposed basket and also for dumping the fuel when required but normally the plates or sectors —13— will be disposed directly over the space —8'— between the sectors —8— of the underlying bottom grate section and inasmuch as they are somewhat wider circumferentially than said space it is evident that the lower grate section —9— may be adjusted angularly limited distances in opposite directions without uncovering the underlying spaces.

It is equally evident, however, that when it is desired to dump the fuel from the grates the grate section —9— may be adjusted to bring its plates or sections —13— into registration with the sectors —8— of the underlying grate section —6— thereby registering the openings between the sectors —13— with the openings —8'— between the sectors —8— and allowing the fuel to fall through the registering openings.

The sectors —8— are each perforated preferably by a series of lengthwise slots —8''— while the sectors —13— of the upper grate section —9— are perforated by a series of similar slots —13''— to allow the finer ashes to sift therethrough, particularly during the shaking operation.

A bottom cap section —15—, Figures 1 and 2, is seated upon the upper face of the upper grate section —9— coaxial therewith and is provided with a relatively short central hub —16— extending into the upper end of the hub —12— and provided with a peripheral key —16'— Figure 3, engaging in a corresponding key-way —9''— in the hub —12— to cause the cap section —15— to rotate with the upper grate section —9— while permitting said cap section to be removed by vertical displacement.

The marginal edges of the cap section —15— extends some distance beyond the inner ends of the openings —13'— between the plates or sectors —13— and are provided with radial slots as shown in Figure 1 to allow the ashes to pass therefrom onto the underlying sectors —13— and —8—, the central portion of the cap section —15— being also perforated as shown in Figures 1 and 2

for the same purpose and to allow air to pass from the ash pit upwardly through the hub —12— and through the cap section —15— into the interior of the basket presently described.

Any suitable means may be provided for oscillating the upper grate section —9— and cap section —15— about a vertical axis for shaking the ashes therefrom and for dumping purposes and, as illustrated, the hub —12—, which is mainly cylindrical and journaled in the hub —4—, extends downwardly below the hub —4— and has its lower end below said hub square or angular in cross section for receiving one end of a crank arm —17— which is held against downward displacement by a pin —18—, Figure 2.

The outer end of the crank arm —17— is connected to the rear end of a link —19— which extends forwardly through an opening —20— in the wall of the ash box —A—, Figure 11, and has its front end provided with a block —21— some distance beyond the front side of the ash box.

A bracket —22— is bolted or otherwise secured to the front side of the ash box for receiving and supporting a hand lever —23— which is movable forwardly and rearwardly and extends some distance below and above the horizontal plane of the link —19— as shown in Figure 11, the lower end of the lever being pivoted at —23'— to the bracket to permit the forward and rearward swinging movement thereof.

The intermediate portion of the lever —23— is connected by a link —24— to the block —21— so that the forward and rearward movement of the lever will be transmitted to the link —19— and thence to the crank arm —17— for shaking the bottom grate section about its axis, Figure 11.

Suitable means is provided to prevent the shifting of the lever —23— and upper grate section —9— operated thereby to their dumping positions and for this purpose a stop dog —25— is pivoted at —25'— to the bracket —22— to swing to and from a position across the front edge of the lever —23— so that when the stop dog is in its operative position it will prevent the forward movement of the lever to its dumping position as shown in Figures 5, 11, 12 and 13 or when the dog is moved to its inoperative position as shown by dotted lines in Figure 12 the forward movement of the grate bar may be continued to the position shown by the dotted lines at the extreme right hand of Figure 11 for moving the upper grate section —9— to its dumping position.

The bracket —22— is also provided with a relatively fixed stop shoulder —28— in the path of movement of the lever —23— for the purpose of limiting the movement of said lever beyond its dumping position when the stop dog —25— is thrown out of the path of movement of said lever.

The basket as 30 forming the upright retaining walls for the fuel is shown as circular and concentric with the axis of the lower and upper grate sections —6— and —9— and comprises a multiplicity of narrow upright grate bars —31— and —31'— of similar construction so that they may be cast in one and the same mold except that certain pairs of the grate bars having the meeting edges registering with the slots —11— in the perforated plates of the lower grate section —6— are provided with outwardly offset and downwardly extending lugs —32— which are seated in the adjacent slots —11— to hold the corresponding bars against radial displacement relatively to the lower section —6—, said lugs being provided with shoulders —33— normally resting upon the upper faces of the adjacent portions of the perforated plates, as shown more clearly in Figures 2, 3 and 9.

The remaining upright grate bars —31'— are supported by interlocking connections with the four pairs of grate bars —31— and by similar interlocking connections with each other in such manner that they may be assembled one upon the other in sequence circumferentially from a given point in the periphery in a manner presently described. The basket —30— is adapted to be supported in a horizontal plane within the combustion chamber of the heater between the upper face of the upper grate section —9— and lower wall of the fuel inlet opening of said heater so that the lower ends of the bars —31— and —31'— will be disposed in a plane slightly above the upper grate section —9— to enable the latter to be oscillated for shaking or dumping purposes without interference with the upright grate bars of the basket.

The major portions of the grate bars —31— and —31'— from the bottom upward are substantially vertical and parallel so that the corresponding portion of the basket will be substantially cylindrical but the upper ends —31''— of said bars are deflected outwardly in planes inclined to the vertical and are gradually widened from the vertical portions to their upper edges to compensate for the increased diameter of the basket as shown more clearly in Figure 2.

That is, the diameter of the upwardly flaring upper end of the basket corresponds more or less closely to the inner diameter of the combustion chamber in which the entire grate as a unit is installed so that the upright cylindrical portions of the basket will be in spaced relation to the walls of the combustion chamber to permit the free circulation of air from the ash pit upwardly through the perforations in the bars —31— and —31'— at different levels and thereby to better support the combustion of the fuel within the basket.

In order to establish the interlocking con-

nexion between the meeting edges of the upright grate bars —31— and —31'— corresponding edges of each bar are provided with a pair of outwardly projecting hook-shaped flanges —40— while the opposite edges are provided with ribs —41— in correspondingly spaced relation vertically and adapted to be engaged by the adjacent hooks for holding the bars against circumferential displacement and also assisting in holding the bars against inward or outward displacement.

As previously stated the bars —31— having the downwardly projected bosses —32— are supported directly upon the lower grate section —6— while the remaining upright bars —31'— are supported by the bars —31— and for this purpose corresponding edges of the bars are provided with L-shaped projections —42— while their opposite edges are provided with lugs —43— adapted to rest upon the bottoms of the projections —42— when the bars —31— and —31'— are assembled.

The L-shaped projections —42— and lugs —43— are disposed in substantially the same horizontal planes between and in vertically spaced relation to the hooks —40— and ribs —41—, the walls of the L-shaped projections —42— being disposed in a horizontal plane just under the lower edges of the lugs —43— as shown more clearly in Figures 2, 8 and 14.

The hook-shaped projections —40— are adapted to engage their respective ribs —41— by relative vertical sliding movement of adjacent bars one upon the other and in like manner the lugs —43— are adapted to engage their respective L-shaped lugs —42— by a relative vertical sliding movement of adjacent bars one upon the other until limited by the engagement of the lugs —43— with the bottom of the lugs —42— as shown more clearly in Figures 2 and 8.

The most convenient manner of assembling these grate bars to form the basket —30— is to first place the bars —31— in operative position with their pendant lugs —32— seated in the slots —11— on the underlying bottom grate section —6— and their hook-shaped lugs —40— in engagement with the corresponding ribs —41— on adjacent edges of said bars, as shown in Figure 9.

The remaining bars —31'— are then successively interlocked with the adjacent bars —31— and with each other by downward sliding movement thereof relatively to the bars previously installed thereby bringing the hook-shaped members —40— into interlocking engagement with their respective ribs —41— and at the same time bringing the lugs —43— into engagement with the bottoms of the L-shaped lugs —42— which limit the downward movement of the bars —31— so that the latter will rest in substan-

tially the same horizontal plane to form the basket —30—, as shown in Figure 2.

Assembly

5 One of the important advantages of the construction described is that the various parts may be easily and quickly installed in the combustion chamber and ash box of a heater by simply removing the grate commonly used and providing the ash box with suitable supports for the ends of the main tubular supporting bars —1— with their collars —2— thereon.

10 That is, the bars —1— are first installed and properly secured in operative position in parallel relation and in the same horizontal plane and preferably extend forwardly and rearwardly of the ash box.

15 The spider section comprising the hub —4— and arms —3— is then placed in operative position in the saddles —2'— which are adjustable along and upon the supporting bars —1— to properly position them for receiving the arms —3— as shown in Figure 5.

20 The lower grate section —6— is then placed upon the upper end of the hub —4— so that its downwardly projecting flanges —10— and lower end of the hub —7— may rest upon the upper face of the spider section.

25 The upper bottom grate section —9— is then placed in operative position with its hub —12— extending downwardly through the hub —4— and its central portion resting upon the ball bearings —14— after which the cap section —15— may be placed in operative position with its hub —16— seated in the upper end of the hub —12— and its outer marginal edges resting upon the perforated sectors —13—.

30 The upright bars —31— are then placed in operative position in the slots —11— on the lower grate section —6— after which the remaining bars —31'— are successively placed in operative position from the top downwardly to interlock their lugs —40— with the ribs —41— and also to engage their lugs —43— in the adjacent L-shaped lugs —42— which latter hold the sections —31'— against further downward movement while permitting their free upward displacement when necessary or desirable.

35 After the parts have been assembled in the manner described the crank arm —17— may be placed from the underside upwardly on the square lower end of the hub —12— and held in operative position by the insertion of the key —18—.

40 The link —19— is then connected to the outer end of the crank arm —17— and to the block —21— on the outer end of the link —24— as shown in Figures 11 to 13 inclusive thus connecting the hub —12— of the oscillatory upper grate section —9— to the shaking and dumping lever —23—.

When the stop dog —25— is in operative position in the path of outward movement of the lever —23— it will serve to limit the backward and forward movement of said lever to effect a corresponding oscillating movement of the upper grate section —9— for shaking purposes.

45 When it is desired to dump the grate the stop dog —25— may be rocked from its operative position shown by full lines in Figure 12 to the position shown by dotted lines in the same figure thus permitting the lever —23— to be rocked forwardly a greater distance until limited by the stop —28—, this increased movement serving to shift the upper grate section —9— until its perforated sectors —13— are registered with the perforated sectors —8— of the lower grate bottom section —6— thereby establishing in this instance four relatively large openings between said perforated sectors through which the ashes and other solid contents formerly contained in the basket are entirely discharged from said basket into the underlying ash pit.

50 What I claim is:

1. In a heater grate, a substantially flat and horizontal grate section having radially projecting perforated sectors in uniformly spaced relation circumferentially at its periphery and a basket composed of relatively narrow upright perforated bars arranged edge to edge circumferentially around the axis of and positioned above said grate section, some of the bars being supported upon said section and provided with means supporting the next adjacent bars out of engagement with said section.

55 2. In a heater grate, lower and upper coaxial grate sections, the upper section being capable of oscillation about a vertical axis relatively to the lower section, each grate section being provided with radially projecting perforated sectors arranged in uniformly spaced relation circumferentially at their peripheries, the sectors of the upper section being movable into and out of registration with the spaces between the sectors of the lower section, and a fuel receiving basket mounted upon the lower section beyond the periphery of the upper section.

60 3. In a heater grate of the character described, a pair of horizontal supporting bars arranged in parallel spaced relation and each provided with a pair of saddles adjustable thereon, a grate-supporting frame having radially projecting arms seated in said saddles, lower and upper grate sections supported on the grate-supporting frame coaxial therewith, said upper section being capable of oscillation about a vertical axis, each grate section, being provided with radially extending perforated sectors in uniformly spaced relation circumferentially and of greater surface area than the spaces between them, the sectors of the upper section

being movable into and out of registration with the spaces between the sectors of the lower section.

4. In a heater grate of the character described, a pair of horizontal supporting bars arranged in parallel spaced relation and each provided with a pair of saddles adjustable thereon, a grate-supporting frame having radially projecting arms seated in said saddles, lower and upper grate sections supported on the grate-supporting frame coaxial therewith, said upper section being capable of oscillation about a vertical axis, each grate section being provided with radially extending 10 perforated sectors in uniformly spaced relation circumferentially and of greater surface area than the spaces between them, the sectors of the upper section being movable into and out of registration with the spaces 15 between the sectors of the lower section, and a basket supported on the lower section coaxial therewith and provided with vertical openings therethrough.

5. In a heater grate of the character described, a pair of horizontal supporting bars arranged in parallel spaced relation and each provided with a pair of saddles adjustable thereon, a grate-supporting frame having radially projecting arms seated in said saddles, lower and upper grate sections supported on the grate-supporting frame coaxial therewith, said upper section being capable of oscillation about a vertical axis, each grate section being provided with radially extending 30 perforated sectors in uniformly spaced relation circumferentially and of greater surface area than the spaces between them, the sectors of the upper section being movable into and out of registration with the spaces between 35 the sectors of the lower section, and means for oscillating the upper grate section.

6. In a heater grate of the character described, a pair of horizontal supporting bars arranged in parallel spaced relation and each provided with a pair of saddles adjustable thereon, a grate-supporting frame having radially projecting arms seated in said saddles, lower and upper grate sections supported on the grate-supporting frame coaxial 45 therewith, said upper section being capable of oscillation about a vertical axis, each grate section being provided with radially extending perforated sectors in uniformly spaced relation circumferentially and of greater surface area than the spaces between them, the sectors of the upper section being movable into and out of registration with the spaces between the sectors of the lower section, means for oscillating the upper section, a stop for 55 limiting the movement of said oscillating means and thereby limiting the angle of oscillation of the grate section, said stop being movable from its operative position to an inoperative position to permit a further movement of the adjusting means and resultant in- 60

creased angular movement of the upper grate section for dumping purposes.

7. In a heater grate, a pair of frame-supporting bars arranged in parallel spaced relation, a grate-supporting frame having arms extending diagonally across said bars, saddle members movable along and upon said bars and provided with seats for receiving and supporting said arms, and a grate supported upon said frame. 70

8. In a heater grate, a horizontal grate-section and a basket composed of relatively narrow upright bars arranged edge to edge circumferentially about a vertical axis, some of said bars being supported upon the grate section and provided with means for supporting the adjacent bars out of engagement with the grate section. 80

9. In a heater grate, frame-supporting bars adapted to be mounted upon and within the base of the heater, a frame extending across said bars and provided with supporting members adjustable relatively thereto along and upon said bars, and a grate supported upon said frame. 90

10. In a heater grate, frame-supporting members adapted to be supported upon and within the base of the heater, a frame extending across said members, slides on the frame adjustable relatively thereto along and upon said members for supporting the frame, and a grate mounted upon said frame. 95

11. In a heater grate, a grate-supporting frame having a central tubular hub and arms radiating outwardly therefrom, and a grate supported on the frame and provided with lugs interlocked with said arms to hold the grate and frame against relative circumferential movement. 100

12. In a heater grate, a pair of bars supported within and upon the base of the heater in parallel spaced relation, a frame extending across said bars and provided with radially adjustable feet resting upon the bars and a grate supported upon the frame. 105

In witness whereof I have hereunto set my hand this 29th day of October, 1928.
